Patented October 27, 1903.

UNITED STATES PATENT OFFICE.

CLARENCE M. WOOLLEY, OF CHICAGO, ILLINOIS, ASSIGNOR TO AMERICAN RADIATOR COMPANY, A CORPORATION OF NEW JERSEY.

DESIGN FOR A RADIATOR.

SPECIFICATION forming part of Design No. 36,607, dated October 27, 1903.

Application filed August 27, 1903. Serial No. 171,026. Term of patent 14 years.

To all whom it may concern:

Be it known that I, CLARENCE M. WOOLLEY, a citizen of the United States, residing in Chicago, county of Cook, and State of Illinois, have invented a new, original, and ornamental Design for Radiators, which is fully illustrated in the accompanying drawing, forming a part hereof, and in which the radiator is shown in perspective.

I claim as my invention—

The design for a radiator, illustrated in the accompanying drawing.

In testimony whereof I have signed my name to this specification in the presence of two subscribing witnesses.

CLARENCE M. WOOLLEY.
